UNITED STATES PATENT OFFICE.

JOHN T. FIELD, OF POCATELLO, IDAHO.

TYPEWRITER.

Application filed February 11, 1921. Serial No. 444,176.

To all whom it may concern:

Be it known that I, JOHN T. FIELD, a citizen of the United States, and a resident of Pocatello, in the county of Bannock and 5 State of Idaho, have invented a new and Improved Typewriter, of which the following is a full, clear, and exact description.

My invention relates to a typewriter, and aims to provide certain new and useful improvements, more particularly with regards 10 to the type-bar and hanger for the same.

It is well appreciated, in connection with typewriters, that considerable difficulty has been experienced incident to the fact that the 15 type-bars of all styles of machines have necessitated a certain amount of adjustment, to compensate for play which comes into being incident to wear.

It has been heretofore proposed to provide 20 elements associated with the segment of a typewriter which have served to crowd the bodies of the type hangers, one against the other, to overcome play, but this has not served to compensate for the wear at the 25 points of pivotal connection of the hanger and type-bars.

Further difficulty has been experienced, in connection with what is known as a "double bank" machine, in that it has been 30 necessary to employ two series of hangers, one for each bank, to provide points of pivotal suspension for the type-bars, then complicating the structure.

Having these defects in mind, I have constructed 35 certain improvements in typewriters, and more particularly with respect to the means and method of suspension of the type-bars, whereby primarily, a medium will be provided permitting an individual, as well as an aggregate adjustment for these 40 members, permitting of wear to be compensated for.

A further object of my invention is the provision of improvements in typewriters, 45 which will serve to reduce the complication incident to a "double bank" machine.

Further objects of my invention will appear in the following specification and drawings, which latter present practical embodiments of the same, and in which—

Figure 1 is a partly fragmentary plan view of a typewriter segment and illustrating the type hangers and bars associated therewith.

Fig. 2 is an enlarged sectional view taken

on the line 2—2, and in the direction of the arrow indicated in Fig. 1.

Fig. 3 is an end view of the segment illustrated in Fig. 1.

Fig. 4 is a bottom perspective view of 60 one of the hangers.

Fig. 5 is a partly sectional plan view of one of the type bars.

Fig. 6 is a side view thereof.

Fig. 7 is a fragmentary, partly sectional 65 face view of a portion of the segment and illustrating the type-bars applied to the hangers associated therewith.

Fig. 8 is a fragmentary plan view of the segment illustrating my invention as applied to a "single bank" typewriter.

Fig. 9 is an enlarged sectional plan view taken on the line 9—9, in the direction of the arrow indicated in Fig. 8.

Fig. 10 is a fragmentary view of a portion of the segment and illustrating the improved type of hanger utilized in connection with a "double bank" machine, the type-bars being adapted to be arranged in staggered relationship in this type of machine. 75

Fig. 11 is a fragmentary perspective view of the hangers and segment as illustrated in Fig. 10, and showing one of the hangers removed therefrom to illustrate the underlying construction.

Referring now more particularly to Fig. 1 it will be seen that the reference numeral 15 indicates a segment of a typewriter which mounts type hangers 16, which are movable within certain limitations within the body 90 of the segment 15, their movement being limited by any suitable means such as bolts 17.

With regard to achieving an aggregate adjustment of these hangers in the manner 95 set forth in the objects of the specification, a pair of set screws 18 are conveniently utilized, these elements being associated with the ends of the segment 15 and contacting directly with that type hanger next 100 adjacent to the ends of the segment. Also one of the hangers, positioned approximately intermediate the extremities of the segment 15, may be fixed as has been indicated by the reference numeral 19, and it will 105 thus be appreciated that an aggregate adjustment of the hangers may be had by tightening one set of screws 18, so as to bear against the outermost hanger 16, thus jamming these elements toward the center hang-

er secured as at 19, this expedient obviously precluding any play on the part of any of the individual hangers 16. This operation will serve to clamp those hangers between the screws 18 and the fixed hanger 19 together, and a further adjustment of this nature may be secured by adjusting the second set of screws 18 thus tightening all of the hangers.

10 Contrary to the conventional construction, reference being had to Fig. 4, it will be seen that each of the hangers 16, preferably includes a body portion presenting a reduced end 20. Shoulders 21 are also provided and the body of the hanger 16 tapers from these shoulders toward its outer end, thus presenting a wedge shape. Also it will be noted that the set screws 18 co-operate with the bodies of the hangers 16 at points to each side of the shoulders 21 and by virtue of this construction and the fact that the individual hangers contact with the next adjacent hangers adjacent the shoulder portions only, it will be appreciated that a tightening of either the outer or inner screws will result in a limited rocking motion being effected by the hangers, thus serving to provide an aggregate limited rocking as well as lateral adjustment for the same.

It will also be noted, reference being had to Fig. 4, that the outer end of each of the type hangers 16 terminates in what might be conveniently termed an ear 22, which latter provides a pair of openings 23 preferably arranged one above the other. These openings serve as a bearing for providing pivotal connection to the type-bars, and referring to Figs. 5 and 6 it will be seen that these type-bars include a body provided with a conventional reenforcing rib 25 and mounting upon the outer end the type 26. The opposite end of the body 24 is preferably formed with a reduced portion and by coupling the plate 27 to this end of the body 24 I provide at the rear end of the body of the type-bar a pair of arms 28 spaced one from the other and each carrying a suitable element 29 adapted to cooperate with one of the openings 23, whereby to provide a pivotal suspension means for the type-bar. Despite the aggregate adjustment described in the preceding paragraph in connection with the set screws 18, it will be appreciated that it will be impossible to obtain that nicety of adjustment requisite to equally tensioning the stroke of each of the type-bars, and at the same time to prevent any play at their points of pivotal suspension, and with this in view I conveniently utilize a taper plug 30 extending between the arms 28 and co-operating therewith to effect a movement of these arms one with respect to the other 65 when the plug is projected or retracted.

Thus the arms 28, being moved the elements 29 will be moved further apart or toward each other, and it will thus be appreciated that by this expedient I am able to individually adjust each of the type-bars in a proper manner, and by virtue of the fact that a pair of openings 23 are associated with each of the ears 22, it will be obvious that a separate series of bearing elements may be dispensed with.

75 Referring now more particularly to the construction illustrated in Figs. 8 and 9 it will be seen that the segment is constructed in the usual manner and serves to mount type hangers affording pivotal suspension means for the type-bars, which in this latter form are constructed in any desired manner.

80 Referring more particularly to these type hangers it will be seen, however, that each of the same preferably includes a pair of wedge shaped members 32 co-operating together to provide a substantially triangular shaped body and a pair of ears 33 are fixed one to each of the wedge shaped members 32 and provide openings 34 forming points of pivotal connection for the type-bars. These latter elements may include in the usual manner, as has been illustrated in Fig. 8, a shank 35, carrying type 36 at its outer end and being formed with a pair of lugs 37 adapted to extend one into each of the openings 34 of next adjacent ears 33.

85 To effect the adjustment desired, i. e., individual compensation for wear of each of the type bars, I preferably utilize taper plugs 38, which extend between the faces of co-operating members 32 and into the body of the segment 31, it being obvious that a projection of these plugs will result in 90 a movement of the ears 33, one with respect to the other.

95 Thus an individual adjustment will be provided by virtue of the fact that the bearing openings 34, co-operating to retain the lugs 37 on the single type-bar, may be varied in distance from each other, thus serving to 100 tighten or loosen the bearing to achieve the result desired.

105 Now with a view of simplifying the construction of a "double bank" machine, utilizing this principle, it will be noted, reference being had to Fig. 11, that adjacent type hangers have their bodies arranged in staggered relationship with respect to each other 110 and to provide proper co-operating portions with these bodies it will be noted that the bodies of the members 32 forming the underlying series, have recess portions 39 cut in their upper faces, the upper layer of the members 32 being formed with corresponding recesses 40 whereby a lap joint is provided, insuring a firm interlocking of each of the type hangers with respect to each other and the segment is assured upon suit- 115 120 125 130

able screws 41 being applied to the upper layer of hangers.

From the foregoing it will be appreciated that I have constructed certain improvements in connection with a typewriter, in that individual adjustment, as well as aggregate is permitted on the part of each of the type-bars, aside from the fact that means for simplifying the construction of a "double bank" machine are provided.

It obviously will be appreciated also that numerous modifications of structure may readily be resorted to without the least departing from the scope of my claims which 15 are—

1. In a typewriter, a segment, a plurality of type hangers arranged transversely of the segment and side by side, each of said hangers including a body having oppositely located side edges converging toward an end of the body, between which side edges the body is of maximum width, each said body also having a terminal ear, a plurality of type bars pivoted between the ears of adjoining bodies so that the ear of each body is connected to the ear of the bodies on both sides by a plurality of type bar pivots, and means adjacent an end hanger and cooperating with the same for adjustment to force 25 all the hangers into intimate contact with each other at the points of maximum width of the hangers.

2. In a typewriter, a segment, a plurality of hangers arranged transversely of the 35 segment and side by side and having portions of maximum width between the ends of the hangers, retaining means for the hangers permitting a limited rocking movement of the various hangers simultaneously,

and adjustable means engaging an end hanger for imparting such a rocking movement to the hangers.

3. In a typewriter, a segment, a plurality of type hangers arranged transversely of the segment and side by side and carrying 45 projecting ears equipped with holes, a plurality of type bars each having pivot points on opposite sides, the parts being so designed and arranged that the alternate type bars may be pivotally mounted on the 50 hangers on said ears at different perpendicular differences from the plane of the segment with the hangers and interposed type bars forming a continuous chain of relatively movable links, and adjustable means 55 acting on one end of such chain for simultaneously rocking all the hangers in planes parallel to the plane of the segment.

4. In a typewriter, a segment, a plurality of hangers arranged transversely of the segment and side by side and having portions of maximum width between the ends of the hangers, and an adjusting means engaging an end hanger for acting on the line of 60 hangers along lines offset from the line of maximum width of the hangers to simultaneously rock all the hangers about lines 65 perpendicular to the plane of the segment.

5. In a typewriter, a segment, a plurality of type hangers supported by said segment, 70 certain of said hangers including a body formed with a reduced end portion, and an ear adjacent the opposite end of said body, said body being tapered and presenting shoulders adjacent its reduced end portion, 75 and type bars adapted to be movably supported by the ears of said hangers.

JOHN T. FIELD.
